LOUIS A. HAWTHORNE, OF NEWARK, NEW JERSEY, ASSIGNOR TO STEEL UTILITIES INCORPORATED, A CORPORATION OF NEW YORK.

LABELING-MACHINE.

1,345,006.

Specification of Letters Patent. Patented June 29, 1920.

Application filed July 26, 1917. Serial No. 182,890.

To all whom it may concern:

Be it known that I, LOUIS A. HAWTHORNE, a citizen of the United States, residing at Newark, in the county of Essex and State of New Jersey, have invented certain new and useful Improvements in Labeling-Machines, of which the following is a specification.

This invention relates to machines for labeling bottles or other containers, and has 10 special reference to an automatic type of machine having improved features to facilitate the speedy and accurate handling of the containers, and the proper affixing of the labels thereto.

15 The primary object is to provide a novel, simple and reliable machine for affixing labels to bottles or other containers wherein the label magazine, label-affixing, and the container handling instrumentalities are synchronized in such a manner that the desired labels may be readily placed on the bottles or other containers accurately, expeditiously and without danger of breakage.

25 A further and more specific object of the invention is to provide novel means for handling the labels. That is to say, it is proposed to provide a novel arrangement of special instrumentalities for both supplying the label with adhesive as it is released from 30 the storage magazine, and then bringing it into position to be affixed to the container, as well as to coordinate therewith the handling of the containers in a manner to insure the proper results.

35 With the above and other objects in view which will more readily appear as the nature of the invention is better understood, the same consists in the novel construction, combination, and arrangement of parts hereinafter more fully described, illustrated and claimed.

40 A preferred and practical embodiment of the invention is shown in the accompanying drawings, in which:—

45 Figure 1 is a top plan view of the labeling machine.

Fig. 2 is a side elevation thereof.

50 Fig. 3 is an enlarged detail view of the lever for controlling the movement of the label magazine.

Fig. 4 is a side elevation looking from the receiving end of the machine.

55 Fig. 5 is a vertical cross sectional view on the line 5—5 of Fig. 2.

Fig. 6 is an enlarged detail sectional view 55 of the auxiliary label affixing device.

Fig. 7 is a detail sectional view of the delivery end of the container guide-way.

Fig. 8 is a detail longitudinal section showing a modification of the invention 60 which proposes to provide a third adhesive supplying belt for the labels.

Fig. 9 is a top plan view of the construction shown in Fig. 8.

Fig. 10 is a cross sectional view of the constructions shown in Figs. 8 and 9.

Similar reference characters designate corresponding parts throughout the several figures of the drawings.

The present machine primarily and essentially includes in its organization a container-advancing device designated generally as A, and a labeling unit B whose various instrumentalities are synchronized with the said container-advancing device which may be, and preferably is the prime mover for the entire apparatus. That is to say, the present invention provides means for advancing a bottle or other container to and through a labeling unit that fundamentally 70 includes a pair of spaced parallel label-carrying ribbons or belts R—R. These ribbons or belts automatically take the labels singly from a magazine M, supply the adhesive thereto, and position the same in the path of travel of the container for the purpose of affixing the same thereto. In this latter connection it may also be noted that there is preferably included in the general organization of the machine a self-adjusting 80 auxiliary affixing device C which assists in the affixing operation by firmly pressing the gummed portions of the label to the bottle. 85

90 Referring particularly to the structural features of the machine in which is consolidated the foregoing features, it will be observed from Fig. 2 that the bottle moving or advancing device preferably includes a bed 1 which may consist as shown, of the opposite frame members 2 and 3 which are secured together by the spacing bolts 4, as will be seen from Figs. 5 and 6, to provide the necessary clearance for the mounting of sprocket wheels and the other instrumentalities necessary to the proper operation of 95 the apparatus. The opposite frame members 2 and 3 are preferably formed at their upper sides with the vertical guide walls 5—5, 100

105

and the horizontal flange portions 6-6, which coöperate to provide a guideway floor for the container guide or runway G formed by the parallel walls 5-5, and which, as shown in Fig. 6, terminate short of each other to provide a central clearance slot 7. Directly beneath the flange portions 6-6 the said frame members 2 and 3 are provided with suitable conveyer guide channels 8-8 which are intended to receive and guide a container advancing conveyer designated generally as 9 and consisting of the pivotally connected bars or slats 10 having on their under side suitable sprocket engaging socket portions 11. At regular spaced intervals, this conveyer 9 is provided with the upstanding propeller blades 12 which project through the clearance slot 7 in the floor of the container guideway for the purpose of engaging and advancing the containers therein in single spaced order as the conveyer is steadily and continuously driven by the sprocket 13 journaled as at 14 between the frame members 2 and 3 at one end of the bed of the apparatus.

With further reference to the container guideway or runway G formed by the upstanding walls 5-5 and the horizontal flange portions 6-6, it will be observed that the same is curved at its delivery end D, as shown in Fig. 1, whereby one of the side walls is intersected by the slots 7 so that the blades 12 may pass freely on as the conveyer 9 makes its cycle. This formation of the delivery end of the conveyer conveniently provides for deflecting the bottles or other containers, after they have passed through the labeling unit B, out of the line of their normal path of travel through the machine to suitable crating apparatus or the crating position for the purpose of assembling in shipping crates. And, owing to the novel formation of the conveyer guide channels 8-8 which receive the flat slats or bars 10 of the conveyer, it will be clear that the latter has a positive and steady mounting in the frame whereby greater stability and rigidity will characterize the movement of the conveyer to insure the positive and accurate impelling of the containers in the guideway G of the propelling blades 12.

Carried by the intermediate portion of the bed 1 of the apparatus is the frame-work of the labeling unit B. This framework preferably includes the opposite side walls 15 and 16 which constitute the major portion of the superstructure of the labeling unit, and the depending shaft-carrying elements 17 and 18 which are also spaced apart, as seen from Figs. 5 and 6 of the drawings, to accommodate the sprocket wheel 19 which meshes with the socket elements 11 of the conveyer 9 and is carried on the shaft 20 journaled in the said elements 17 and 18. This sprocket wheel 19 and shaft 20, being

engaged with the continuously moving conveyer 9, constitute the prime actuating means for all of the label affixing instrumentalities. Accordingly, as will be observed from the drawings, the shaft 20 has keyed to one end thereof a driving gear 22 which is of mutilated formation, that is, only provided over part of its periphery with gear teeth while the balance thereof is smooth, whereby the same may have an intermittent driving engagement with a pinion 23 carried by the shaft 24 also journaled in the shaft carrying elements 17 and 18 and fitted with the wheels 25 and 26 which are arranged in the separate adhesive supply chambers 27 and 28 formed at the lower ends of the said elements 17 and 18. Thus, it will be apparent that these wheels 25 and 26 in addition to performing the function of supplying adhesive to the ribbons R-R, also constitute the driving means therefor, as will presently appear.

With further reference to the pinion 23 mounted on the shaft 24 which drives the wheels 25-26, it will be observed from the drawings, particularly Fig. 2, that the same is only provided throughout a part of its periphery with enough gear teeth to mesh with the teeth of the gear 22, and is also provided with a concave portion for engaging with a smooth portion of the periphery of the gear 22. This arrangement, therefore, causes the shaft 24 to be locked at certain intervals during the operation of the apparatus whereby the wheels 25 and 26 and consequently the ribbons R-R will be held at rest during the interval when the container is being advanced between the ribbons and against a label thereon to thereby fix the label in its position on the container. Further, it may be noted at this point, that the propelling blades 12 are so spaced on the conveyer 9 that the sprocket wheel 19 which drives the shaft 20 will make one complete revolution while the conveyer is advancing the distance equal to the space between a pair of blades, and in turn the complete revolution of the shaft 20 will cause the gear 22 to impart a complete revolution to the shaft 24 through the toothed portions of the gears 22 and 23. Thus, every time the conveyer advances a distance equal to the space between the blades 12 it first causes the ribbons R-R to be coated with adhesive by the wheels 25 and 26 to receive a label from the magazine M, and then come to rest at a point where the label will be positioned directly across the path of the moving container.

In order to properly distribute the adhesive coating on the wheels 25 and 26, there is provided in each of the adhesive chambers 27-28, a suitable wiper member 29 which is mounted on a shaft 30 supported in the walls of the adhesive chamber and provided

with the exterior arm 31 which is held under tension by a spring 32 whereby the free end of the wiper will be yieldably held in contact with the periphery of the adhesive supplying wheel.

The continuous ribbons R—R previously referred to, are preferably of relatively thin flexible steel, and are arranged in spaced paired relation in the framework of the labeling unit B to provide for the passage therebetween of a bottle or other container for the purpose of affixing a label thereto. These ribbons are each carried by upper and lower sets of paired idler pulleys 33—33 10 and 34—34 which are respectively journaled in the upper part of the walls 15 and 16 of the superstructure of the labeling unit and the walls of the shaft carrying elements 17 and 18. And, as previously explained, 20 the ribbons are driven by the adhesive supplying wheels 25 and 26 which have a frictional engagement with the set of pulleys 34—34. For the purpose of maintaining these ribbons sufficiently taut and to take up 25 any unnecessary slack therein the upper sets of idler pulleys 33—33 are preferably mounted on shafts S—S journaled in the adjustable blocks 35, as shown in Figs. 2, 4, and 5 of the drawings. And, in order to 30 provide a suitable support for the span of the ribbons between each pair of pulleys 33—33 of the upper sets of idlers, the walls 15 and 16 are provided with the upstanding platen members 36, so that when the magazine 35 M is lowered to place a label on the ribbons, the latter will be firmly supported to insure the accurate placing of the labels 40 thereon.

In connection with the magazine M which holds the labels which are supplied to the adhesive coated ribbons R, it will be observed that the same preferably consists of a suitable label containing frame 37 which holds the labels in such a manner that the 45 lowest one may be easily released, and the entire frame is adjustably carried by means of suitable nuts 38 on the rods or standards 39 which are slidably supported at substantially their intermediate portions in the guides 40 formed in the upper ends of the walls 15 and 16, and are also guided at their lower ends as indicated at 41 (Fig. 5) in the bed 1 of the apparatus. The lower ends of these standards 39 have a working engagement 50 with the peripheries of a pair of duplicate operating cams 42 rigidly carried by the main operating shaft 20, whereby during the operation of the apparatus, the entire magazine may be alternately raised and lowered to deposit at the desired instant a label on the ribbons R.

Since the shaft 20 which carries the cams 42 operates continuously and the ribbons R—R also run at intermittent intervals as 60 long as the conveyer runs, it is desirable to

provide means for preventing labels from being deposited on the ribbons, except when a bottle is passing through the guideway G and about to enter within the limits of the labeling unit B. Therefore, in order to 70 lock the magazine M in its elevated position, except when a bottle is passing through the labeling unit, a suitable restraining device is provided for the magazine.

The device essentially comprises a sleeve 75 43 which surrounds one of the standards 39 and is provided in its upper portion with a notch 44 which is adapted to receive a pin 45 carried by the rod 39 when the sleeve is rotated a sufficient distance to cause the pin 80 to slide off of the upper edge 43^a thereof. That is to say, one of the rods 39 carries a pin 45 which normally rests upon the upper edge of the sleeve 43, whereby the entire magazine will be held in its elevated 85 position, or on the other hand, when the sleeve is turned so that the pin 45 drops into the notch 44, the magazine will be permitted to drop whereby the ends of both rods 39 may be operatively engaged by the 90 working periphery of the cams 42. For the purpose of maintaining the sleeve 43 in its normal position, that is, so that the pin 45 rests on the upper surface thereof, a spring 46 is secured to the outer end of a 95 lever 47 carried by the sleeve, and the other end of said spring is made fast as at 48 to a suitable pin or its equivalent projecting from the side of the wall 15. And, in order to release the magazine for operation at the 100 desired time, the arm 47 of the sleeve 43 has pivotally connected therewith a link 49, the other end of which is pivotally connected with a bell crank lever 50 pivoted as at 51 to one of the walls 5 of the guideway 105 G, whereby its arm 52 projects into the guideway to be engaged by the passing containers.

Accordingly, it will be apparent that when a container is passing through the guideway 110 G, it will strike against the arm 52 which, through the instrumentalities just described, will turn the sleeve 43 a sufficient distance to enable the pin 45 to drop into the slot 44 and thus permit the entire 115 weight of the magazine to rest upon the working periphery of the cams 42. The peripheries of these cams are such that the magazine will be permitted to drop and deposit a label on the ribbons R—R therebelow, and the continuous rotation of the shaft 20 which carries the cams 42 will after the magazine has been lowered, cause the same to again be elevated and thereby lift the pin 45 out of the notch 44 whereby 120 the spring 46 will turn the sleeve back to its normal position and place the pin on the upper edge 43^a thereof.

After the label has been deposited on the ribbons R by the lowering of the magazine, 130

the continued movement of the said ribbons will carry the label into position to be fixed by the container, at which time the ribbons will come to rest owing to the smooth periphery of the gear wheels 22 and 23 coming into contact. Then, the continuous movement of the container through the guideway under the influence of the blade 12 of the conveyer will cause the container to push the label from the ribbons so that the gummed end portions thereof will engage the exterior of the container to thereby affix the label. However, as previously indicated, as the container passes from between the ribbons R—R which both supply the label with adhesive and position the same for affixing, it is engaged by the auxiliary label wiper or affixing device C. This device is in the nature of a gate, and preferably consists of a pair of vertically disposed container engaging rollers 53 carried upon suitable arms 54, which are in turn carried by the vertically disposed pin-like elements 55 loosely journaled as at 56 in one of the side walls 5 of the container guideway, and carry at their lower ends suitable crank arms 57 whose free ends are fitted with depending bracket rods 58 which are connected by a suitable spring 59, whereby both of the rollers 53 and 54 are yieldably held in the position shown in Fig. 1 of the drawings. Thus, when a container is pushed in the guideway between the ribbons R—R, it will be engaged by the rollers 53 which will firmly wipe over the label and thereby press it against the exterior of the container to positively insure the affixing thereof.

However, while this device is desirable since it positively and firmly presses the label on to the bottle, it is not entirely indispensable, especially under certain conditions of use. That is to say, when the ribbons which carry the labels are spaced to permit of the free passage of the bottles therebetween, or in other words, are spaced farther apart than the diameter of the containers as shown in the present drawings, the device C is especially useful, but where the ribbons are arranged relatively close together, *i. e.*, less than the diameter of the container as in the case of applying small labels, the ribbons themselves will exert sufficient pressure on the gummed ends of the labels and cause the same to adhere to the bottles, since as the latter are forced between the ribbons they will turn on their axes, because of their thin and flexible nature to permit the passage of the bottle, and thus produce the necessary pressure for causing the label to adhere to the outer surface of the container. In the latter case, it will of course be clear that the device C may still be utilized, but the affixing of the label is primarily accomplished by the act

of pushing the container between the spaced parallel belts or ribbons which are coated with adhesive and carry the labels from the magazine into the position to be engaged by the passing container.

The form of the invention above described only provides for gumming the opposite end portions of a label and thus this form of the apparatus is primarily intended for use in affixing labels of a conventional form which usually cover at least one-half of the diameter of the container. Under some conditions, it may be desirable to supply this type of label with additional adhesive, for instance, in the center thereof, and furthermore, in the case of diamond shaped labels or labels which provide a relatively small area at each end for receiving adhesive, it is especially desirable that the center of the label also be supplied with adhesive. Accordingly, it is proposed to provide a construction involving a third ribbon or adhesive-supplying tape. This form of the invention is illustrated in Figs. 8, 9, and 10 of the drawings, and involves no departure from the essential features of construction of the machine shown in the rest of the drawings. That is to say, in this modification, it is contemplated to provide a third ribbon R' positioned between the two ribbons R—R heretofore described, and located at the top of the labeling unit.

As will be observed from Fig. 8, this ribbon R' is mounted to run on the pulleys 33^a which are mounted on the same shafts S—S 100 as the paired sets of idlers 33—33, whereby the same movement of the ribbons R—R will be thereby imparted to the center ribbon R'. The outer surface of this ribbon R' is supplied with adhesive through the provision of an auxiliary adhesive holding chamber 60 which is mounted between the walls 15 and 16 and has journaled therein an adhesive supplying roller 51 whose periphery is engaged by the free end of a wiper spring 62 fastened as at 63 to the outer surface of the adhesive holding chamber as will be clear from Fig. 8. Thus, this arrangement provides for supplying adhesive to the center of the label without interfering in any way with the passage of the bottles or other container between the ribbons R—R.

Referring now to the manner of operation of the apparatus, it will be seen that since the conveyer 9 is driven continuously by the sprocket wheel 13, the bottles or other containers will be impelled in the guideway G by means of the blades 12 at regular spaced intervals, to and through the labeling unit B. The continuous operation of the conveyer also causes a continuous operation of the sprocket 19 and the shaft 20, and consequently the continuous rotation of the gear 22 which has an intermittent engage-

ment with the pinion 23 mounted on the shaft 24 that carries the wheels which move the ribbons R—R and also supply the same with adhesive. Thus, the continuous movement 5 of the conveyer causes the intermittent movement of the ribbons R—R whereby the same will come to rest in a position to hold the label in the path of the moving container.

10 When a container is impelled along the guideway G it first strikes the arm 52 of the bell crank 50 which operates the sleeve 43 of the restraining device for the magazine M, thus causing the pin 45 on one of the rods 39 of the magazine to drop into the notch 44 whereby the ends of the rods 39 will be permitted to engage with the zenith of the working peripheries of the rotating cams 42. In the meantime, the continuous movement 15 of the conveyer will cause the advance of the ribbons R—R to carry the adhesive thereon to a position beneath the label magazine where the same will be lowered and a label deposited on the ribbons or 20 wiped thereby from the magazine. Then, the continued movement of the conveyer will cause the zenith of the cams 42 to engage the ends of the rods 39 and cause the magazine to be lifted whereby the pin 45 will be 25 placed on the upper edge 43a of the sleeve 43 and the arm 52 will fly back into the guideway C. Simultaneously, the label which was placed on the adhesive coated 30 ribbons R—R will be advanced into position to be placed on the container, and then temporarily held while the continuous movement of the conveyer causes the bottle to push the label from the belts, and then engage the rollers 53 of the auxiliary affixing 35 device C which, as previously explained, assist in affixing the label by pressing the ends thereof into engagement with the exterior of the container. As the container is advanced by the conveyer, through the device 40 C, it strikes against the curved wall of the delivery end D of the guideway G and is ready to be sent to the crating machinery or the like, while at the same time, the blade 12 which has been pushing the container 45 through the guideway G passes on through the clearance wall 7.

Without further description, it is thought that the many features and advantages of the present invention will be readily apparent, and it will, of course, be understood that various changes in the form, proportion, and minor details of construction may be resorted to without departing from the spirit of the invention or scope of the appended claims.

I claim:

1. A labeling machine including a frame, a labeling unit consisting of spaced continuous imperforate flexible label carrying ribbons, means for applying adhesive to the

outer surfaces of said ribbons, a label holding magazine, rods having an adjustable engagement at their upper ends with said label holding magazine, guides carried by said frame for causing the magazine carrying rods to move vertically, means for shifting said rods to bring the magazine in position to deliver a label to the imperforate ribbons, and means for advancing a container between the ribbons and against a label carried thereby. 70

2. A labeling machine including a pair of spaced endless label carrying belts arranged at each side of a container guide-way, means arranged beneath the container guide-way 80 for supplying adhesive to said belts, and an auxiliary adhesive supplying device arranged between said spaced belts and above the container guide-way and out of the path of the containers. 85

3. A labeling machine including a frame having a container guide-way, upper and lower sets of pulleys supported in said frame at each side of the guide-way, continuous label carrying belts mounted on said pulleys, 90 means for supplying adhesive to the belts as they pass over the lower sets of pulleys, a label magazine positioned above the upper sets of pulleys, and an auxiliary adhesive supplying device arranged between 95 the upper sets of pulleys and beneath said label carrying magazine and also between the said belts.

4. A labeling machine including a container guide-way, means for propelling the 100 containers in said guideway, means for positioning adhesively coated labels across said guideway, a magazine for supplying labels to said means, means for causing said magazine to move toward and from said label affixing means, said means comprising a pair of duplicate cams actuated by the movement of the means for propelling the containers in the guideway, and a restraining device for maintaining said magazine in its elevated position. 105

5. A labeling machine including a container guideway, means for propelling the containers in said guideway, means for positioning adhesively coated labels across 115 said guideway, a magazine for supplying labels to said means, means for causing said magazine to move toward and from said label affixing means, and a restraining device for maintaining said magazine in its elevated position, said restraining device consisting of a laterally projecting pin carried by the frame of the magazine, a spring tensioned notched sleeve, a link connected with said sleeve, and a trip-arm connected 120 with said link and having a portion thereof disposed in the path of containers passing through the guideway. 125

6. A labeling machine including a pair of adhesive supplying and label carrying rib- 130

- bons mounted in spaced relation, paired sets of pulleys for carrying said ribbons, means for supplying adhesive to the outer faces of said ribbons, a label magazine for supplying labels to said ribbons, means for causing a container to pass between said ribbons, mutilated gearing operatively connected with said means for causing the containers to pass between the ribbons to cause the intermittent movement of the ribbons, and cams associated with said gearing for causing the operation of the label magazine.
7. A labeling machine including a pair of adhesive supplying and label carrying ribbons mounted in spaced relation, paired sets of pulleys for carrying said ribbons, means for supplying adhesive to the outer faces of said ribbons, a label magazine for supplying labels to said ribbons, a guideway formed between said ribbons, a container propelling device working in said guideway, means for continuously driving said device, combined adhesive supplying and ribbon driving wheels engaging with said ribbons, gearing including mutilated gears between said container propelling device and said wheels, and cam means operated synchronously with the mutilated gearing for causing the operation of the magazine.
8. A labeling machine including a pair of endless adhesive supplying and label carrying ribbons mounted in spaced relation, means for impelling a container between said ribbons, means driven by said means for impelling the containers for actuating the ribbons, a magazine for supplying labels to the ribbons, said magazine comprising a

label carrying frame, standards carrying the frame, and a restraining device having means for operatively engaging one of said standards and adapted to be operated by passing containers for controlling the movement of the magazine.

9. A labeling machine including a pair of endless adhesive supplying and label carrying ribbons mounted in spaced relation, means for impelling a container between said ribbons, gearing driven by said means for impelling the containers for actuating the ribbons and having cams associated therewith, a magazine for supplying labels to the ribbons, said magazine comprising a label carrying frame, standards carrying the frame at one end and having their opposite ends engaging said cams, and a container controlled restraining device engaging one of said standards.

10. A labeling machine including a pair of spaced adhesive supplying and labeling positioning ribbons, means for supplying labels to said elements, a guideway having a slot arranged between said elements, conveyer traveling beneath said guideway and having container propelling blades projecting through said slot, and means actuated by the conveyer for controlling the movement of the magazine and ribbons.

In testimony whereof I hereunto affix my signature in the presence of two witnesses.
